Attorney

UNITED STATES PATENT OFFICE.

ERVIN W. TATE, OF DEXTER, MAINE, ASSIGNOR TO NATIONAL METAL SEAL CORPORATION, OF DEERING JUNCTION, PORTLAND, MAINE, A CORPORATION OF MAINE.

CLOSURE-APPLYING TOOL.

1,261,458.

Specification of Letters Patent.

Patented Apr. 2, 1918.

Application filed October 16, 1916. Serial No. 125,809.

To all whom it may concern:

Be it known that I, ERVIN W. TATE, a citizen of the United States, residing at Dexter, Penobscot county, State of Maine, 5 have invented certain new and useful Improvements in Closure-Applying Tools, of which the following is a specification.

This invention relates to devices for applying closures to containing vessels, and 10 particularly to a hand tool for seating a rotatable closure in hermetic sealing relation upon its container.

This device may be used to apply closures of various constructions, but for the purpose 15 of illustration a cap is shown having a depending skirt or rim, which is knurled or otherwise roughened to permit the cap to be grasped and readily rotated, and provided with a plurality of spaced inturned fingers 20 adapted for engagement with a series of cam lugs on the container mouth. The cap is applied to the container and seated by rotation. In filling the containers for shipment it is required that they be sealed 25 tightly, especially where the content is of a volatile nature, or where it is likely to be spoiled by exposure to air.

The production of such closures in commercial quantities makes liable the development 30 of inequalities in the coacting sealing surfaces, and if these inequalities are not corrected, the seal will not be sufficiently perfect to protect the content from deterioration by access of air thereto, evaporation, 35 or the like.

The object of my invention is to provide a simple and readily manipulatable device, illustrated as a hand tool for applying rotatable closures to containing vessels and for 40 automatically correcting any interruption to the intended continuous bearing surfaces of closure and container, thereby to secure an impervious joint in every vessel sealed.

The construction and operation of my device is fully disclosed in the specification which follows. In the drawings accompanying that specification I have shown an embodiment which not only well illustrates the principles of my invention but is in 50 itself a form found satisfactory in use and well adapted to the requirements of manufacture. Throughout the specification and drawings, like reference characters are cor-

respondingly applied and in these drawings—

55

Figure 1 is a view illustrating the manner of use of my device, the cap and tool being shown in section.

Fig. 2 is an underneath plan view of my device with the cover plate for one of the 60 pawls removed.

Fig. 3 is an enlarged detail section, and

Figs. 4 and 5 are an elevation and a bottom plan view, respectively, of the cap.

In carrying out my invention in the form 65 shown I provide a head adapted to be held in the hand and formed with a seat or receiving recess for the closure and a pair of gripping devices carried by said head and disposed for engagement with the rim of the 70 cap whereby to turn the cap when the head is turned in one direction. These gripping devices preferably consist of oppositely mounted pawls adapted for engagement with the knurled rim of the cap and which 75 rim thus constitutes a ratchet surface. The pawls are pivotally mounted and spring pressed to allow the cap to be inserted therepast and find its seat and to automatically move back to position to engage the cap rim 80 and turn it when the head is turned in the proper direction. When the head is turned in the opposite direction the pawls ride idly over the ratchet surface of the cap rim without imparting rotation to the cap.

85

I have indicated at 1 a head provided with a strap or other handle 2, to enable the head to be effectively grasped. The head 1 has a depending annular rim 3 defining with the body portion of the head proper an annular 90 cap receiving recess or seat 4, into which a cap is adapted to be inserted from below and to loosely fit.

The cap rim is recessed at opposite points as indicated at 5. Pivoted at 6, in said recesses is a pair of pawls 7, the free ends of which project in opposite directions into the cap receiving recess in position to engage opposite points of the knurled or otherwise roughened cap rim. The pawls 7 are held 100 from movement in one direction by suitable pins 8, disposed to bear thereagainst, and are yieldable in the opposite direction to allow the cap to be inserted therepast and find its seat. The movement of the pawls in this 105 direction is resisted by coiled springs 10,

mounted on laterally projecting studs 11 on the pawls and bearing against the rear walls of the recesses 5 at their opposite ends. These springs automatically re-act against 5 the pawls to return them to position after they have yielded to allow a cap to be inserted therewith. The pawls and the recesses in which they are mounted are covered by suitable cover plates 13 which are screwed or 10 otherwise fastened to the under face of the rim 3.

The specific type of closure for which the tool shown is especially adapted consists of a metallic or other flexible cap 14 having 15 a depending annular rim 15 which is knurled or otherwise roughened as shown and which is provided with a series of spaced inturned lug engaging fingers 16.

The fingers of the cap co-operate with a 20 series of spaced cam lugs 17 about the mouth of a glass or other rigid containing vessel 18, whereby the cap is drawn tightly onto the container as it is turned relative thereto. In the particular embodiment shown, which 25 is a hand-tool, the peripheral configuration of the head 1 is such as to provide a series of spaced suitably curved indentations, best shown in Figs. 2 and 3, into which the fingers of the operative's hand are adapted to fit when the tool is manipulated, the palm of the hand bearing against the top face of the head 1, and the strap 2 overlying and bracing the back of the hand, and as here shown being provided with a buckle whereby the 30 tool may be strapped to the hand. In addition to this function, the strap 2 provides a convenient suspension loop for hanging up the tool on any suitable hook when not in use.

40 In using my device, the cap is inserted from below into the receiving recess of the head 1, or picked up by applying the tool to the caps as they lie on the bench. The pivoted pawls 7 automatically yield inwardly and immediately return to engage the cap rim after the cap has been inserted. The tool is then placed over the mouth of a containing vessel with the inturned fingers of the cap registered with the spaces or 45 gaps between the series of lugs about the container mouth, whereupon the tool is turned in the seating direction of the cap. This causes the exposed ends of the pawls to engage the knurled rim or ratchet surface of the cap, thereby compelling the loosely fitting cap to turn with the turning movement of the head until the limit of turning movement of the cap on the container is reached. The cap is now seated 50 firmly upon the container, and in its seating movement has forcibly overcome any irregularities existing between the co-operating bearing surfaces of cap and container, thereby insuring an impervious seal. When 55 the cap has reached the limit of its seating

rotation the head is disengaged by a simple separating movement. The container is now sealed for shipment. Should the head be turned in a direction opposite to the seating direction of rotation of the cap the 70 pawls ride idly past the knurls of the cap rim without imparting turning tendency to the cap.

While I have shown and described my device in its application to a closure and container of a specific type, it will be understood that the device is capable of use with other types of closures, and I do not therefore limit myself to this application alone of my invention, but reserve the right to employ my device in any capacity where it will satisfactorily perform its intended functions.

Various other modifications in the form and constructions of my invention may obviously be resorted to if within the limits of the appended claims.

What I therefore claim and desire to secure by Letters Patent is:

1. In combination, a head having an annular rim defining a cap receiving space, said rim provided with a recess opening laterally into said space, and a cap gripping member pivoted in said recess and lying wholly therein with its free end projecting 90 into said cap receiving space.

2. In combination, a head having an annular rim defining a cap receiving space, said rim provided with a recess opening laterally into said space, and a cap gripping pawl pivoted in said recess with its free end projecting into said cap receiving space, and a spring in said recess backing said pawl and normally urging its free end into said space and allowing said pawl to 105 turn on its pivot to permit the insertion of a cap therewith into said cap receiving space.

3. In combination, a head having an internal recess constituting a cap seat, and a pair of spaced gripping members pivotally mounted upon said head and projecting into said recess, said members adapted to be moved away from the cap by the insertion of the cap therewith into the recess, and springs acting against said members to automatically return them to cap engaging position after the cap has been seated in said recess.

4. In combination, a rotatable seat in 120 which a closure having a roughened rim constituting a ratchet surface is adapted to be loosely received, and a pair of pawls pivoted to said seat and having their free ends extending in opposite directions into 125 the receiving recess for the closure to engage opposite points of said ratchet surface and cause the closure to rotate with the seat.

5. In combination, a rotatable head having an internal recess constituting a seat 130

- for a cap having a roughened rim, and a pawl carried by said head and projecting into said recess for engagement with the rim of said cap to cause the cap to turn with the head when the head is turned in one direction and ineffective to turn the cap when the head is rotated in the opposite direction.
6. In combination, a rotatable head having an internal recess constituting a seat for a cap having a roughened rim, and a pair of oppositely pivoted pawls on said head projecting into said recess and yieldable in one direction to permit the cap to be inserted therepast and automatically returning to position to engage the rim of said cap to cause the cap to turn with the head when the head is turned in one direction and ineffective to turn the cap when the head is rotated in the opposite direction.
- 10 7. In combination, a rotatable head having an internal recess constituting a seat for a cap adapted to be applied to a container by rotation, and having oppositely pivoted engaging devices disposed in the direction of seating rotation of the cap and adapted to engage opposite portions of the cap rim and rotate said cap when the head is turned in one direction and to ride idly over said rim without imparting turning tendency to the cap when the head is rotated in the opposite direction.
8. In combination, a rotatable head having an internal recess constituting a seat for a cap adapted to be applied to a container by rotation, and having oppositely pivoted engaging devices disposed in the direction of seating rotation of the cap and adapted to engage opposite portions of the cap rim and rotate said cap when the head is turned in one direction thereby to correct any inequalities in the bearing rim surfaces of cap and container in the seating of the cap on the container.
9. In combination, a head having a depending internally recessed rim providing a
- cap seat, and a gripping member yieldably mounted in said rim with its engaging face projecting slightly into said recess, said member adapted to be moved outwardly by the insertion of a cap therepast into said recess and to automatically return to position to engage the cap rim after the cap has found its seat in said recess.
10. In a hand tool of the class described, a head having a peripheral configuration adapting it to be readily grasped in the fingers of one hand and having an overlying handle portion between which and the top face of the head, the hand is adapted to be inserted with the palm bearing against said top surface and the fingers grasping adjacent portions of said periphery.
11. In a hand tool of the class described, a rotatable head providing a seat for a closure, said head adapted to be grasped in the hand and having an overlying handle portion adapted to engage the back of the hand whereby the tool may be secured to the hand, and means mounted upon said head and adapted to engage the closure to cause the closure to rotate with the rotation of the head.
12. In a hand tool of the class described, a head providing a seat for a closure and having a peripheral configuration of such form as to provide a series of spaced indentations into which the fingers of the hand may fit and having a face against which the palm of the hand may bear whereby the head may be conveniently grasped and rotated, and means mounted upon said head and adapted to engage the closure to cause the closure to rotate with the rotation of the head.

In testimony whereof I affix my signature in presence of two witnesses.

ERVIN W. TATE.
